UNITED STATES PATENT OFFICE.

JOHN REID, OF NEW YORK, N. Y.

FURNACE-FRONT.

1,380,739.

Specification of Letters Patent. Patented June 7, 1921.

Application filed November 20, 1919. Serial No. 339,388.

To all whom it may concern:

Be it known that I, JOHN REID, a subject of the King of Great Britain, and residing at 30 Church street, in the city of New York, 5 in the State of New York, in the United States of America, have invented a new and useful Furnace-Front, of which the following is a specification.

The invention relates to furnace fronts as 10 described in the present specification and illustrated in the accompanying drawings that form part of the same.

The invention consists essentially of the 15 novel construction and arrangement of parts, whereby the various new features introduced contribute to the proper combustion of the fuel and to better facilities for installation and shipment.

The objects of the invention are to 20 increase the steam generating properties of oil fuel furnaces and thereby save in the consumption of fuel and benefit by the efficiency gained; to facilitate the assembly of the parts and the adjustment of the air feed 25 after assembly; to eliminate the expense, inconvenience, and delays incident to the repairs, which may be necessary in marine installations *en route*; to further develop the Reid type of furnace with a view to standardization and with a view to rapid and efficient installations and to effect improvements concerning directly or indirectly the following patented inventions and applications pending: Numbers 1,318,331, October 30 35 7th, 1919, 1,297,247, March 11th, 1919, Serial Nos. 317,537, filed August 14th, 1919, 317,538, filed August 14th, 1919, 299,361, filed May 23rd, 1919, 323,177, filed September 11th, 1919, 291,362, filed April 19th, 1919, and 40 334,355, filed October 29th, 1919; and generally to provide as an article of commerce and manufacture a reliable, cheap and strong furnace front.

In the drawings, Figure 1 is an elevation 45 of the back plate, showing the rear portions of the intermediate parts.

Fig. 2 is a vertical sectional view of the complete front.

Fig. 3 is a perspective detail of the main 50 cone deflector.

Fig. 4 is a perspective detail of the regulating sleeve.

Fig. 5 is a perspective detail of the air cylinder.

Fig. 6 is a perspective detail of the inner 55 cone deflector and adjusting sleeve.

Fig. 7 is a longitudinal sectional detail of the main cone deflector.

Fig. 8 is a longitudinal sectional view of the assembled air cylinder and regulating 60 sleeve.

Fig. 9 is an elevation of the back plate, showing another arrangement of the intermediate parts.

Fig. 10 is a vertical sectional view of the 65 front as illustrated in Fig. 8 without the valve gear.

Fig. 11 is a detail, showing a simple form of rod control for the main and the inner 70 cone deflectors.

Fig. 12 is an elevation of the back plate, showing the intermediate parts in an oil burning assembly without valves other than the regulating sleeve.

Fig. 13 is an elevation of the back plate, 75 showing a rotatable regulating sleeve taking the place of all other valves and operated in front.

Fig. 14 is a vertical sectional view of the form illustrated in Fig. 12.

Fig. 15 is a vertical sectional view of the form illustrated in Fig. 13.

Like numerals of reference indicate corresponding parts in the general groups of figures respectively illustrating the different 85 forms of the invention.

Referring to the drawings, one of the important features of this invention is the air register in its three coöperating parts, the air cylinder 1, the regulating sleeve 2, and 90 the cone deflector 3, though the general make up of the furnace front materially contributes to its efficiency.

The air cylinder 1 is a tubular piece of metal having a flange 4 at the inner end and 95 an annular row of air ports 5 adjacent to said flange. The sleeve 2 fits over the cylinder 1 and is adjusted to regulate the size of the ports 5.

The cone deflector 3 slides into the air 100 cylinder 1 and the radial vanes 6 extending from the rim 7 through to the small end 8 of the cone project in a radial direction to the interior wall of the cylinder and thereby divide the inrushing air, so that it reaches 105 the brink of the cone end in separated streams and shoots over the edge in the direction of the spreading oil spray.

The cone shell 3 is outwardly in the shape of the frustum of a cone, which results in a 110 bell like casing for the passage of the oil pipe 9 centrally therethrough, the nozzle 10

being at the inner extremity slightly beyond the inner and small end of the cone deflector 3. An inner cone deflecting plate 11 is mounted on the pipe 9 in an inverted 5 position in relation to the setting of the cone deflector 3 and adjacent to the outlet end 8 of the latter.

It will be thus seen that the air in a forced 10 draft or other system is directed into the combustion chamber in many distinct paths and by two main roads, the outside and the inside, the outside road being subdivided into the many inclined paths, separated by the vanes 6, into which the air flows either 15 beyond the outer or inner ends of the sleeve 2, therefore at the beginning or toward the ends of the inclined paths, in the latter case through the ports 5. The inside road is 20 through the cone shell or bell like casing and the air in this case flows behind the rim 7 and is deflected by the minor cone deflector 11 from which in Figs. 4 to 10 it strikes the inner wall of the cone deflector 3 and is emitted from the outlet 8 to the burning 25 oil gas, and in Figs. 1 to 8 is emitted to the flame between the minor cone 12 and the adjustable collar 13 and the minor cone 12 in this form of the invention is supported by the blades 14 separating a plurality of 30 passages. The minor cone 12 guides the flow of air so that it follows the spread of the flame from the nozzle and saves undue force of air at the nozzle outlet, the same 35 remarks applying equally to the minor cone 11.

The structure shown in Figs. 1 and 2 is 40 very well suited to the oil burning air register already described and in this form of front the back plate 15 is shown as having 45 permanently a rear half 16 of an air deflecting or baffle plate above the air register in the form of an arch, the front half 17 extending rearwardly from the front plate 18, both front and back plates having openings 50 for the installation of the air burning equipments, as for example, the air cylinder 1 is inserted from the rear side of the back plate 15 and the flange 4 is rigidly secured to the latter. The regulating sleeve 2 is 55 mounted on the cylinder 1 from the opening in the front plate 18 and similarly the deflecting cone 3 is inserted in the cylinder 1 and slidably arranged so as to increase or decrease its distance from the closure plate 55 19, that supports the pipe 9 within the inwardly projecting flange 20 supporting the sleeve 21, on which the collar 13 is adjustably mounted.

The closure plate 19 is rigidly secured 60 and the regulating sleeve 2 and adjustable collar 13 are set, so as to obtain the best results in regard to the proper combustion of the oil.

In Fig. 12 the sleeve 2 and collar 13 are 65 shown as adjusted by rods 22 and 23 extend-

ing through the front plate and by such an arrangement an engineer can regulate his fires according to existing conditions regarding the quality and the quantity of oil feed and the force of the air draft.

The flare in front and rear halves 24 and 70 25 separates the front and back plates at the lower half portion and is in the form of an arc-shaped intermediate wall flanged at its upper ends 26, which at their angle 75 form seats for the side valves 27, the other seats 28 being at the lower ends of the baffle wall formed by the extensions 16 and 17.

The packing 29 is introduced between the meeting ends of the baffle and flare walls, 80 so that an air pocket is formed between the front and back plates and the only opening thereinto is by a lower door 30, which may be used for natural draft and which corresponds to the ash pit door in a coal burning 85 front.

The operating means for the side valves is not shown in Figs. 1 and 2, as it is obvious that they may be turned by a handle on the end of a shaft projecting through the front 90 plate and illustrated in many of the aforesaid pending applications.

The brick work 31 is built up in a suitable way to accomplish the best results.

The form of the invention as in Figs. 1 95 and 2 is for an oil burning furnace only though a slight modification of the frame will make it readily convertible to a front suitable for a coal burning furnace.

In Figs. 12, 13, 14, and 15, the invention 100 is shown for oil burning furnaces only, though it may be of the convertible type, as that only necessitates a change in the frame. In the four figures mentioned above, the front plate 22 and back plate 93 and intermediate baffle plate 94 and flare 94^a are 105 assembled in any suitable manner or cast as one piece if desired to form the main frame.

The plate 94 turns downwardly at each 110 end above the air register formed of the air cylinder 95 having the ports 96 and receiving the cone deflector 97. In Figs. 12 and 18 the sleeve 98 is similar to the regulating sleeves aforesaid, but takes the place of other valves entirely and is operated by the 115 screw rods 99 turned by the handle 100, and screwing in the turn-buckles 101, which are secured to the sleeve 98.

In Figs. 13 and 15 the air cylinder extends a little further toward the front plate 120 and the sleeve 102 rotates on said cylinder and uncovers ports in the cylinder and brings them into registry with the ports 103 in the sleeve.

The rack 104 is mounted on the sleeve 125 102 and this coacts in turning the sleeve with the gear wheel 105, which is mounted on the shaft 106 and turned by the handle 107. In this way all other valves are dispensed with and the air is admitted to and 130

through the cone deflector and air cylinder according to the openings disclosed in the operation of the regulating sleeve.

In operation the air flows in preferably 5 from an individual heater in a forced draft system, as it will then be more even as to quantity and force. The air entering the front between the plates first strikes the top baffle. This baffle distributes it, so that it 10 flows down each side and upwardly and enters the air register between the rim of the same and the closure plate and reaches the interior and flows therethrough coming into contact with the minor cone deflector, 15 which guides the flow toward the spreading flame. The greatest flow of air passes between the vanes and through the ports in the air cylinder and this flows on to the spreading cone of flame and thus promotes 20 combustion. The optional features regarding frame and valve construction and the shapes of the air pockets, as well as the use of these parts in converting a coal front to an oil front must be particularly emphasized 25 herein, because the removable and adjustable parts bid fair to make complete new fronts out of the several different arrangements of valves, the elimination of valves and the construction of the frame.

30 It has been explained herein that many forms of the invention may be used and it must further be understood that without departing from the spirit of the invention, any changes within the scope of the claims 35 following will be included in the protection accorded.

What I claim is:—

1. In a furnace front, a main frame, having front and back plates spaced by intermediate walls and openings through said plates to the firebox, and an air register having a deflector formed of guide plates mounted on a tubular center piece and supported in a cylinder encircled by an adjustable sleeve.

2. In a furnace front, a main frame, having front and back plates spaced by intermediate walls and openings through said plates to the firebox, and an air register having a cone shaped tubular casing supported within a cylinder and vanes from the outer surface of said casing extending to the inner wall of said cylinder.

3. In a furnace front, a main frame, having front and back plates spaced by intermediate walls and openings through said plates to the firebox, and an air register having a cone shaped deflector with radial vanes therefrom and an oil pipe and air hole therethrough and supported in a cylinder situated in said openings leading to the firebox.

4. In a furnace front, a main frame, having front and back plates spaced by intermediate walls and openings through to the

firebox, an air register having a cone-shaped shell member and radial vanes therefrom supported within a cylinder situated in said openings and having ports regulated by an encircling sleeve and means projecting through said front plate for operating said sleeve.

5. In a furnace front, a main frame, having a front plate and a back plate spaced by intermediate walls and openings through to the firebox, an air register having an air deflecting member supported in a cylinder with air ports therethrough and an encircling sleeve slidably arranged and regulating the openings to said deflector and rods projecting through the front plate and forming means of operating said sleeve.

6. In a furnace front, a main frame, having a front plate and a back plate spaced by intermediate walls and openings to the firebox, an air register having an air deflecting member supported in a cylinder having air ports and situated in said openings and an encircling sleeve slidable on the cylinder, and operating rods having handles on the outer ends and screw adjustments in operative connection with said sleeve.

7. In a furnace front, a main frame, having a front plate and a back plate spaced by intermediate walls and openings through to the firebox and ports above said opening in the back plate, a closure plate, a removable air register having a cylindrical member flanged at the inner end and covering said air ports and having a circumferential row of air ports adjacent to the flange and a plurality of interior passages formed by a deflecting inclined member and a regulating sleeve slidably arranged on said cylinder covering and uncovering said ports and narrowing and widening the opening between the cylinder end and a closure plate for the opening in front plate.

8. In a furnace front, a main frame, having a front plate and a back plate spaced by intermediate walls to form an air pocket therebetween, an air register formed of an outer cone deflector supported in a cylinder introduced through the back plate and removable therefrom and a regulating sleeve on said cylinder, an oil pipe extending through said cone deflector and terminating in a nozzle, and an inner cone deflector inverted in relation to said outer cone deflector and adjustable to and from said nozzle on said oil pipe.

9. In a furnace front, a main frame, having a front and back plate spaced by intermediate walls to form an air pocket therebetween, an air register formed of a cylinder having ports and shipped in from the back, a cone shell member having radial vanes reaching the inner wall of said cylinder, an oil pipe extending through said cone shell

Signed at the city of New York, in the State of New York, in the United States of America, this 17th day of November, 1919. 90

JOHN REID
